Primary Examiner — Cathy A MacCormac(74) *Attorney, Agent, or Firm* — Griffiths & Seaton PLLC; JoAnn M. Seaton(57) **CLAIM**

The ornamental design for a cat scratcher, as shown and described.

DESCRIPTION

FIG. 1 is a front, perspective view of a cat scratcher showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view.

The features shown in broken lines are for illustration only and are portions of the cat scratcher forming no part of the claimed design.

1 Claim, 6 Drawing Sheets(56)
